UNITED STATES PATENT OFFICE.

PASCAL J. SHAMPAY, OF CHICAGO, ILLINOIS. ASSIGNOR TO SHAMPAY BROTHERS, OF CHICAGO, ILLINOIS, A CORPORATION OF ILLINOIS.

CLEANING DEVICE.

1,217,352.

Specification of Letters Patent. Patented Feb. 27, 1917.

Application filed June 19, 1914. Serial No. 846,060.

To all whom it may concern:

Be it known that I, PASCAL J. SHAMPAY, a citizen of the United States, residing at Chicago, in the county of Cook, State of Illinois, have invented certain new and useful Improvements in Cleaning Devices, of which the following is a specification.

This invention relates to a device for cleaning carpets, rugs and the like, and more particularly to a scouring or cleaning brush for such a machine, and the principal object of the invention is to dispose the bristles of the brush in such a manner that the cleaning liquid will be directed by the bristles, as the brush rotates, toward the longitudinal center of the brush, or at least away from the ends thereof.

A further object of the invention is to provide a brush of this kind in connection with an appropriate cleaning fluid receptacle so arranged that the surplus cleaning fluid will not be discharged from the end of the receptacle, between it and the movable member upon which the article to be cleaned is supported.

For the attainment of these ends and the accomplishment of other objects, as will appear, the invention consists in the features of novelty in the construction, combination and arrangement of the several parts generally shown in the accompanying drawing and described in the specification, and more particularly pointed out in the appended claims.

35 In the drawings,—

Figure 1 is a sectional view of a device constructed in accordance with the principles of my invention;

Fig. 2 is a detail longitudinal section of a 40 portion of the device, showing the relation of the parts;

Fig. 3 is a view of a brush constructed in accordance with the principles of my invention, and comprising spiral rows of bristles 45 directed toward each other from the ends of the brush and meeting intermediate the ends, and

Fig. 4 is a view to illustrate the use of the device in connection with an article which is 50 less in width than the width of the cleaning device.

In cleaning devices of this kind, it is customary to employ cleaning brushes in which

the bristles are arranged in rows which are 55 disposed around the brush in a plane transverse to the axis thereof. The brush of the present invention differs from this, in that the bristles are arranged in spiral rows extending from the ends of the brush in opposite directions to a point intermediate the ends of the brush. These cleaning brushes being disposed in a cleaning fluid receptacle, tend to discharge the surplus fluid from the ends of the receptacle between the receptacle 65 and the movable member to which the article to be cleaned is attached. In this way, considerable cleaning fluid is discharged from the receptacle and goes to waste.

In this invention a cleaning brush 6 comprises a core 7, mounted by means of a shaft 8 in a cleaning fluid receptacle 9. One end of the shaft 8 which extends through the end of the receptacle 9 carries a gear 10, or other suitable means, by means of which the 75 brush may be rotated. Disposed above the receptacle 9 is a rotatable drum 11 or other movable support, upon which an article 12 is disposed for cleaning. The article is drawn by the drum against the brush as it 80 rotates, and cleansing fluid is applied to the outer face of the article to be cleaned, by means of the brush. The cleaning fluid receptacle is formed on one side with an extension 13, having a bottom inclined to the 85 receptacle proper. It is provided with a scraper or wiper 13' on the other side, preferably made of rubber or other flexible material, for engaging the article cleaned after it leaves the brush to wipe the cleaning 90 liquid from the article and to prevent the cleaning fluid from exuding or being thrown from the receptacle 9. Disposed at the upper end of the extension is a cleaning fluid discharge pipe 14, with discharge openings 95 15, each controlled by means of a valve on a valve lever 16 having a roller 17 at one end thereof adapted to be engaged by the article to be cleaned, to open the valve. These levers 16 are disposed at intervals along the 100 pipe 14, and only the levers actually engaged by the article to be cleaned are operated, so that there will be no surplus fluid discharged into the receptacle 9.

The brush proper comprises a plurality of 105 rows of bristles 18, extending spirally from both ends of the brush in opposite directions

around the brush, until they meet at a point intermediate of the ends, preferably at the longitudinal center of the brush. The effect of these rows of bristles is that of a double screw, so that, when the brush is rotated in the proper direction the rows of bristles tend to force the cleaning fluid away from the ends of the brush and toward the center thereof. The effect of this is to direct the 5 cleaning fluid to the center and to prevent it from exuding from the ends of the receptacle 9, to as great an extent as possible. It is impossible to fill the space between the drum 11 and the ends of the receptacle, as 10 shown more clearly in Fig. 2, and some outlet is desired for the excess of cleaning fluid in the receptacle. However, this brush tends to direct cleaning fluid toward the center, and when an article of less width than the 15 drum 11 is applied thereto it is preferably disposed at about the center of the drum, so that the bristles at the center of the brush will engage the article to be cleaned, and only the valves 16 which are engaged by the 20 article to be cleaned will be opened, thus directing the cleaning fluid to the brush adjacent the center thereof, approximately the 25 width of the article to be cleaned. The tendency of the rotation of the brush with the 30 oppositely disposed spiral rows of bristles is to keep the cleaning fluid in the center, and therefore the maximum efficiency of the brush and in the use of the cleaning fluid will be obtained, and only when the receptacle 35 9 is full, will the surplus be discharged from the ends.

It should be noted that the brush substantially fills the receptacle in which it operates, or at least is in close proximity 40 to the surface thereof, although this need not necessarily be the case, but the action of the brush is to churn the cleansing fluid, which ordinarily is of soapy consistency, so that a great amount of foam is formed, 45 which fills the receptacle very rapidly and which of course, if means is not provided, tends to escape rapidly from the receptacle at the ends thereof. The disposition of the 50 bristles of the brush in this case is such as to counteract and minimize the tendency of the foam and cleansing material to escape from the ends, to as great an extent as possible.

I claim:

- 55 1. In a carpet cleaning device, a rotary brush having spiral rows of bristles extending in opposite directions from the ends and meeting at points intermediate the ends, and means to feed cleansing fluid to the 60 brush for the width only of the carpet to be cleaned, whereby the brush in rotating tends to confine the cleansing fluid only to the width of the carpet to be cleaned.
- 65 2. In a carpet cleaning device, a rotary brush having spiral rows of bristles ex-

tending from the ends, a close fitting receptacle for the brush having an inclined extension at one side, means to feed liquid cleansing fluid down the inclined extension directly to the brush in accordance with the 70 width of a carpet to be cleaned, the carpet to be cleaned being centered with respect to the brush so that when the brush is rotated in one direction it will tend to sweep the cleansing fluid toward the center of the 75 brush and to confine the cleansing fluid to the width of the carpet to be cleaned.

3. In a cleaning device, a rotatable brush having extending bristles, a close fitting receptacle for the brush in which it is rotatable with a lateral inclined extension at one side thereof, and valve means for discharging cleansing fluid down the said inclined extension directly to the brush in accordance with the width of the carpet to be 80 cleaned.

4. In a cleaning device, a rotatable brush having oppositely disposed spiral rows of bristles meeting intermediate the ends, a close-fitting receptacle for the brush in 90 which it is rotatable, and means to direct streams of cleaning fluid to the receptacle at intervals of its length.

5. In a cleaning device, a rotatable brush having oppositely disposed spiral rows of 95 bristles meeting intermediate the ends, a close-fitting receptacle for the brush in which it is rotatable, and means for discharging fluid into the receptacle, comprising a tube having valved apertures at spaced 100 distances.

6. In a cleaning device, the combination of a cleaning fluid receptacle, of means disposed above the receptacle for carrying an article to be cleaned leaving a discharge 105 space at the ends of the receptacle between it and the said means, a brush having opposite spiral rows of bristles rotatable in the receptacle, means for discharging fluid into the receptacle, embodying an apertured discharge pipe, and valve levers for controlling the openings extending into the path of and adapted to be engaged by the article to be cleaned as it is carried by said member in contact with the brush.

7. A cleaning device comprising a movable member for carrying an article to be cleaned, a receptacle for cleaning fluid disposed adjacent the member and spaced therefrom at the ends to form discharge outlets, a brush rotatable in the receptacle having oppositely extending spiral rows of bristles meeting adjacent the center of the brush, the brush extending into the path of and being adapted to engage the article to be cleaned, a cleansing fluid discharge for discharging fluid to the receptacle, comprising a tube with spaced apertures therein, and valve levers for controlling the apertures extending into the path of and adapt- 120 125 130

ed to be engaged by the article to be cleaned before it reaches the brush, whereby fluid will be discharged to the receptacle for approximately the width of the article to be cleaned, the spiral rows of bristles tending to maintain the cleansing fluid adjacent the center of the brush.

5 In testimony whereof I have signed my

name to this specification, in the presence of two subscribing witnesses, on this 15th 10 day of June, A. D. 1914.

PASCAL J. SHAMPAY.
